US0D1066029S

(12) **United States Design Patent** (10) **Patent No.:** **US D1,066,029 S**
(45) **Date of Patent:** **** Mar. 11, 2025**

(54) **BOTTLE**

(71) Applicant: **Calderco Holdings Group, LLC**,
Jupiter, FL (US)

(72) Inventor: **John P. Calderaio**, Jupiter, FL (US)

(73) Assignee: **Calderco Holdings Group, LLC**,
North Palm Beach, FL (US)

(**) Term: **15 Years**

(21) Appl. No.: **29/836,155**

(22) Filed: **Apr. 25, 2022**

Related U.S. Application Data

(63) Continuation-in-part of application No. 29/711,448, filed on Oct. 31, 2019, now Pat. No. Des. 952,467.

(57) **CLAIM**

The ornamental design for a bottle as shown and described.

DESCRIPTION

FIG. 1 is a front/side perspective view of a bottle showing my design.

FIG. 2 is a bottom/front/side perspective view of the bottle of FIG. 1.

FIG. 3 is a back/side perspective view of the bottle of FIG. 1.

FIG. 4 is a front view of the bottle of FIG. 1.

FIG. 5 is a back view of the bottle of FIG. 1.

FIG. 6 is a first side view of the bottle of FIG. 1.

FIG. 7 is a second side view of the bottle of FIG. 1.

FIG. 8 is a top view of the bottle of FIG. 1; and,

FIG. 9 is a bottom view of the bottle of FIG. 1.

The broken lines in the figures represent portions of the bottle that form no part of the claimed design.

1 Claim, 8 Drawing Sheets
